[57] **CLAIM**

The ornamental design for a brush, as shown and described.

DESCRIPTION

FIG. 1 is a side elevational view of a brush showing our new design;

FIG. 2 is a top plan view thereof;

FIG. 3 is a bottom plan view thereof;

FIG. 4 is an isometric view thereof shown on a reduced scale;

FIG. 5 is an end view thereof taken from the right hand end of FIG. 1.

The side of the brush which is not shown is a mirror image of the side disclosed in FIGS. 1 and 4.

FIG. 1

FIG. 2

FIG. 3

FIG. 4

FIG. 5
